UNITED STATES PATENT OFFICE.

THEODORE F. PHILIPPI, OF EAST ST. LOUIS, ILLINOIS.

BENDING MACHINE.

Application filed September 10, 1923. Serial No. 661,916.

This invention relates to new and useful improvements in machines for bending or circling sections of flanged irons such as angle irons, T-irons, etc., and the objects of the invention are to provide a simple and strong machine which will efficiently form or shape irons of various cross sections into circular or similar shapes.

Further objects of the invention are to provide a machine of the class described having a wide range of adjustments whereby irons of various shapes and sizes may be bent in proper form of desired dimensions and to provide readily operated means for regulating said adjustments.

Still further objects of the invention are to provide means for preventing the sections of material from being distorted while operated upon by the forming members, and to provide simple and automatically adjustable means for actuating the forming members.

Other objects of the invention are to provide a cutting attachment for the machine for cutting the material into sections of proper lengths, and to generally improve upon and simplify the construction of the machine of the class described.

In the accompanying drawings—

Figure 1 is a side elevation of the machine.

Fig. 2 is a plan view of a section of angle iron formed into a circular shape and having an inwardly presented annular flange.

Fig. 3 is a similar view with the flange presented outwardly.

Fig. 4 is a detail view of the forming members and showing a section of angle iron being operated upon to form a ring or hoop having an inwardly presented flange.

Fig. 5 is a similar view showing a T-shaped section of material being operated upon.

Fig. 6 is a detail view of the forming mechanism and showing a section of angle iron being operated upon to form a member having an outwardly presented flange.

Fig. 7 is a front end elevational view of the machine.

Fig. 8 is a detail view taken on line 8—8 of Fig. 1 and showing means for regulating the position of the displaceable feed roller.

Fig. 9 is a vertical cross section taken on line 9—9 of Fig. 1.

Fig. 10 is a horizontal cross section taken on line 10—10 of Fig. 1. 55

Fig. 11 is a horizontal cross section taken on line 11—11 of Fig. 7.

Fig. 12 is a fragmental detail view of the manually operated member utilized for controlling the adjustment of the forming roll. 60

Heretofore, in machines designed for rolling or circling angle irons, the rollers were driven by intermeshing gears and in adjusting such rollers for various sized work, the gears would be moved out of pitch and could not operate in all positions. 65

Consequently, in most of the machines only the feed rollers would be driven and the bending roller would run idle. This arrangement is not satisfactory for various 70 reasons, for instance, more power is required to operate the feed rollers and the latter have a tendency to slip and the bending roller does not operate as accurately as where it is positively driven. 75

In the present invention, all of the rollers including the bending roller are positively driven in the desired direction by a flexible member preferably a chain operating over sprocket wheels fixed to the respective roller 80 shafts.

This flexible chain drive permits easy adjustment of the rollers, without the necessity of adjusting the driven element or chain, as the latter by virtue of its peculiar 85 arrangement is automatically adjusted in cooperation with the rollers, a counter weight being provided to take up the slack in the chain and maintain the latter taut. Thus said chain is held under proper tension 90 at all times and exerts proper pull on each roller shaft and the slipping of the rollers during the rolling process is successfully prevented.

Referring by numerals to the accompanying drawings, 10 indicates the base of the machine on which are supported front end frame 11 and rear end frame 12. A shaft 14 is journaled in suitable bearings formed in said end frames and the rear end of said 100 shaft is provided with a suitable clutch 15 controlled by handle 16 for effecting a driving engagement with a belt driven pulley 17. A pinion 18 is fixed to shaft 14 and meshing with this pinion is a gear 19 which 105 latter is arranged on a shaft 20 journaled in

suitable bearings in base 10. Counter shaft 20 has a pinion 21 which is in mesh with a gear 22 carried by shaft 24 which latter is journaled in suitable bearings in the end frames 11 and 12. The forward end of shaft 24 projects outwardly from end frame 11 and has arranged thereon a feed roller 25 which is held in position by a nut 26 screwed on the threaded portion 24^a of the shaft 24.

End frames 11 and 12 are provided with vertically disposed guideways 27 in which are slidably arranged bearings 28. A shaft 29 is journaled in said bearings and its forward end which projects outwardly from the bearing arranged in end frame 11 has mounted thereon a feed roller 30 which is held in position on said shaft by a nut 31 screw-threaded on the threaded portion of shaft 29.

Feed members 25 and 30 preferably consist of separable sections 25^a and 30^a respectively, arranged in juxtaposed relation and adapted to be spaced from each other by means of spacers or washers 32 to accommodate the flanged or lateral portions of the sections of material. An extension 34 which is fixed to or formed integral with the rear end frame 12 forms a housing for the gear 22 and pinion 18 and is provided with a holder 34^a which is adapted to receive a series of washers 32 so that a supply of washers of various thicknesses is always on hand within easy reach of the operator.

Shaft 29 and roller 30 are adjustable relative to roller 25 by means of a horizontally disposed shaft 35 which is journaled in bearings 36 formed in the upper ends of end frames 11 and 12 and carries at its ends eccentrics 37. Engaging these eccentrics are straps 38 having depending lugs 39 which are pivotally connected to the respective bearings 28 of shaft 29. The rear end of shaft 35 has fixed thereto a handle 40 by means of which shaft 35 may be rocked thereby raising or lowering rollers 30. In order to prevent excessive downward movement of rollers 30 and to maintain the same in their adjusted positions relative to rollers 25, one of the straps, preferably the rear one, is provided with a lug 38^a in which is threaded a set screw 41, the lower end of which is adapted to rest on a lug 12^a formed on and projecting outwardly from the rear end frame 12. The forward strap is split and is provided with outwardly projecting lugs 38^b and fixed to one of said lugs is a U-shaped piece 42 in the ends of which is arranged a cam 44 provided with handle 45.

This cam bears against the other one of said lugs so that when handle 45 is actuated in the proper direction, strap 38 is clamped securely to the respective eccentric 37.

End frames 11 and 12 are provided with guideways 46 which are arranged on one side

of feed rollers 25 and 30 and are angularly disposed relative thereto. Bearings 47 are slidably arranged in said guideways and a shaft 48 is journaled in said bearings and its forward end carries a forming roller 49 which occupies a position in the same plane with rollers 25 and 30. These bearings 47 are adjustably carried by the upper ends of members 50 which operate in suitable bearings formed in said end frames. The lower ends of members 50 have fixed thereto sprocket wheels 51 over which operates a sprocket chain 52. A rod 54 is centrally disposed in parallel with members 50 and the lower end of said rod which is threaded is screw-seated in a bearing 55 which spans and is secured to end frames 11 and 12. Rod 54 has fixed thereto a sprocket wheel 56 which is in engagement with sprocket chain 52 so that when bar 54 is rotated, sprocket wheel 56 operates chain 52 which drives sprocket wheels 51 thereby rotating members 50. These members have threaded engagement with their respective bearings and the pitch of the threads is the same as the pitch of the thread of the lower end of bar 54 so that said bar and members 50 travel at the same speed. The longitudinal movement of bars 50 actuates bearings 47 and cause the positioning of forming roller 49 relative to the material being fed by feed rollers 25 and 30.

Bar 54 which is manually operated by a handle 57 is provided with suitable graduations 58 by means of which the diameter of the ring to be formed may be determined.

The rear end of shaft 48 projects outwardly from the rear end of frame 12 and has fixed thereto a sprocket wheel 59 and the shafts 24 and 29 have fixed thereon sprocket wheels 60 and 61, respectively, and passing over these sprocket wheels and driving the respective shafts 29 and 48 is a sprocket chain 62, as shown in Fig. 9.

In order to permit relative movements of shafts 29 and 48 and maintain their respective sprocket wheels in proper driving engagement with the chain, a weight 64 is suspended from the chain and maintains the same under proper tension. This weight is provided with a suitable roller 65 over which said chain operates and idlers 67 and 68 are suitably supported on end frame 12 in order to provide proper engagement of the chain with sprocket wheels 59 and 60.

The forward end frame 11 is provided adjacent to feed rollers 25 and 30 with a suitable guideway in which is slidably arranged a block 69. The forward end of this block has fixed thereon a guide member 70 which is designed to guide the material to be formed to the forming rollers. This plate is adjustable by means of a hand operated wheel 71 which is arranged on the threaded end of a pin 72 seated in end frame 11 and bears against the rear end of block 69. By

turning wheel 71 in the proper direction, block 69 and plate 70 are moved forwardly while spring 74 interposed between the rear end of member 69 and end frame 11 forces 5 said block and plate 70 rearwardly.

A sliding block 75 provided at its forward end with a guide plate or abutment member 76 is slidably arranged in end frame 11 adjacent to forming roller 46 and is designed to 10 engage the formed portion of the material as it is fed forward by the feed rollers and prevent its distortion or lateral displacement. This block is adjustable by means of a hand wheel 77 which is threaded on a pin 15 78 projecting from end frame 11 and engaging the inwardly turned portion of said block. A spring 79 forces said block inwardly and holds it in engagement with hand wheel 77.

20 Where sections of material are formed into circles of smaller diameter, these would not be engaged by plate 76 on account of the short sections being used and an auxiliary guide or abutment member 80 is utilized 25 for this purpose. This member is arranged above forming roller 49 and is carried by the forward end of a rod 81 which is slidably arranged in a projection formed on bearing 47. The inner end of this rod has threaded 30 engagement with a hand wheel 82 so that by turning said hand wheel, rod 81 and plate 80 are moved forwardly or rearwardly as desired. Hand wheel 82 is provided with an annular groove 84 which is in engagement 35 with a portion 79^a of sliding member 79. When hand wheel 82 is rotated, it is held against lateral movement through the interengagement of groove 84 with projection 79^a, thus providing adjustment of member 80 in- 40 dependently of adjustment of member 76, but when hand wheel 77 is operated, block 79 is moved in the proper direction and through the interengagement of portion 79^a with groove 84 carries hand wheel 82 with it, 45 thereby providing simultaneous adjustment of members 76 and 80.

The cutting attachment for cutting sections of material of the desired length consists of a member 85 arranged on the machine 50 adjacent to the rear end frame 12 and projecting outwardly therefrom and of a cutting member 86 operated from the main shaft 24 of an arm 87. A stationary cutting or shearing member 88 is arranged on frame 85 and cooperates with the movable member 86. Frame 85 is provided with a supporting bracket 89 and a rearwardly projecting rod 90 having adjustably mounted thereon a stop arm 91 by means of which sections of material of proper length are cut. 55

I claim:

1. A bending machine comprising a plurality of cooperating rollers adapted to receive and curve bars of metal, flexible driving means for positively actuating all of said 60

rollers, mechanism for adjusting one of said rollers relative to the others to regulate the curvature of the bar, said mechanism including a longitudinally movable member and means cooperating with said longitudinally 70 movable member for indicating the extent of said curvature.

2. A bending machine comprising a pair of cooperating rollers for receiving and feeding sections of angle iron, a forming roller 75 arranged adjacent to and in cooperative relation with said feed rollers and adapted to engage and curve said sections of iron as the same are fed forward by said feed rollers, the said forming roller being adjustable 80 relative to said feed rollers to regulate the diameter of the curve, flexible driving connections for said feed rollers and said forming roller, and automatic take-up means for maintaining said driving connections at all 85 times in operative engagement with said rollers.

3. A bending machine comprising in combination a pair of cooperating feed rollers adapted to feed forward sections of metal 90 bars, a movable bearing box for one of said rollers, an eccentrically mounted member having pivotal connection with said box, a lever for actuating said eccentric member, a forming roller cooperating with said feed 95 rollers for engaging and curving the sections of material fed to it by said feed rollers, said forming roller being adjustable relative to said feed rollers to vary the curvature of said material, abutment members 100 arranged adjacent to said rollers for guiding the material while it is being operated upon, and flexible means for positively actuating all of said rollers.

4. A bending machine comprising a pair 105 of cooperating feed rollers adapted to receive and feed forward sections of metal bars, a forming roller arranged in cooperative relation with said feed rollers and adapted to engage and curve the material fed to it by said feed rollers, a series of guide members arranged adjacent to said rollers for guiding the material operated upon, flexible means for driving said rollers, and manually operable means for adjusting certain of said guide members independently of the others. 110

5. A bending machine comprising feed mechanism adapted to receive and feed forward sections of angle irons, a forming roller arranged in cooperative relation with said feeding mechanism for curving said sections of angle irons, a guide member arranged in cooperative relation with said forming roller for guiding the material 120 while it is being operated upon, means for adjusting said guide member, an auxiliary guide member arranged adjacent to said forming roller for engaging and guiding comparatively short sections of material, 125 130

and means for adjusting said auxiliary guide member independently of the other guide member.

6. A bending machine comprising feeding mechanism adapted to receive and feed forward sections of flanged irons, a forming roller arranged in cooperative relation with said feeding mechanism for engaging and curving the sections of material fed to it, a guide plate in cooperative relation with said forming roller for engaging the material operated upon and preventing lateral distortion thereof, an auxiliary guide member arranged adjacent to said forming roller for engaging comparatively short sections of material, and means for simultaneously adjusting said guide plate and said guide member.

7. A bending machine comprising a support, feed roller shafts journaled in said support, cooperating feed rollers arranged in said shafts and adjustable laterally thereon, a bending roller shaft journaled in said support, a bending roller arranged on said shaft in cooperative relation with said feed rollers, sprocket wheels fixed to said shafts, an endless chain operating in said wheels and driving said shafts, means for operating said chain, and a counter-weight engaging said chain for maintaining it under tension and in proper driving engagement with said wheels at all times.

8. A bending machine comprising in combination a stationary frame, a bearing box fixedly mounted therein, a shaft journaled in said bearing box, a feed roller fixed to one end of said shaft, a movable bearing box mounted in said frame for vertical movement, a shaft journaled in said bearing box in vertical plane with the first shaft, a second feed roller fixed to said last-mentioned shaft in cooperative relation with the first roller, a bearing box mounted in said frame for movement in angular direction relative to said feed rollers, a shaft journaled in said angularly movable bearing box, a roller fixed on said shaft and disposed in the path of the work fed by said feed rollers and adapted to curve said work, said angularly movable bearing box being adjustable to regulate the curvature of said work, a sprocket wheel fixed to each of said shafts, a chain for engaging and positively driving all

of said sprocket wheels, and a counter-weight including an idler for engaging said chain and maintaining it in proper driving relation with all of said sprocket wheels and at the same time permitting relative movement of the movably mounted shafts.

9. A bending machine comprising in combination a plurality of cooperating rollers adapted to receive and curve sections of metal bars, one of said rollers being adjustable in a straight line and angularly relative to the plane passing through the axes of the other rollers to vary the distance between it and the point of work engagement of the other rollers for regulating the curvature of the work, means including a flexible chain drive for positively actuating all of said rollers, laterally disposed abutment members for guiding the work when operated upon by said rollers and means for adjusting said abutment members laterally.

10. A bending machine comprising in combination a pair of cooperating feed rollers adapted to receive and feed forward sections of metal bars, the axes of said feed rollers being disposed in a vertical plane, means including a manually operable lever for quickly displacing one of said rollers in said vertical plane, a forming roller cooperating with said feed rollers and adjustable angularly relative to the plane passing through the axes of the other rollers, flexible driving means for positively actuating all of said rollers at all times and a counter-weight for maintaining said driving means taut.

11. A bending machine comprising in combination a pair of cooperating feed rollers, a forming roller arranged in cooperative relation therewith for operating upon sections of material fed to it by said feed rollers, said forming roller being adjustable angularly relative to the plane passing through the axes of the other rollers, guide members arranged adjacent to said rollers for guiding the material laterally, actuating means including a flexible member for positively driving all of said rollers and means for adjusting said guide members laterally relative to said rollers.

In testimony whereof I hereunto affix my signature this 6th day of Sept., 1923.

THEODORE F. PHILIPPI.
